UNITED STATES PATENT OFFICE.

EARL W. ROBERTS, OF DETROIT, MICHIGAN, ASSIGNOR TO THE ROBERTS BRASS MANUFACTURING COMPANY, OF DETROIT, MICHIGAN, A CORPORATION OF MICHIGAN.

SPRINKLER.

Application filed March 6, 1922. Serial No. 541,303.

The invention relates to sprinklers for use in automatic sprinkler systems and has for its object the provision of a simple form of sprinkler in which the closure for the casing head is mounted upon the nozzle head and out of the path of the spray passing from the nozzle head. With this and other objects in view, the invention resides in the novel features of construction as more fully 5 hereinafter set forth.

In the drawings:

Figure 1 is a longitudinal section through a sprinkler embodying my invention;

Figure 2 is a similar view showing the 15 nozzle head with the closure for the casing head in extended position.

1 is the casing head threadedly engaging at its lower end the stand pipe 2 of the automatic sprinkler system. The upper end 20 of the casing head is substantially flush with the ground, it preferably extending but slightly thereabove. 3 is the nozzle head movable within the casing head 1 and adapted to extend outwardly through the 25 opening 4 in the upper end of the latter, outward movement of the nozzle head being limited by means of the annular inwardly extending flange 5 at the upper end of the casing head engaging the outwardly extending 30 annular flange 6 at the lower end of the nozzle head. The nozzle head 3 is bell-shaped and has at its upper end the discharge orifice 7 through which the water passes. 8 is a core secured within the nozzle 35 head near its upper end and provided with the inclined peripheral grooves 9 for effecting a whirling action of the water passing through the discharge orifice so that a conical spray is formed.

40 When the sprinkler is not in use, the nozzle head 3 occupies a position within the casing head 1, as shown in Figure 1, so that the sprinkler does not present an obstruction at an appreciable distance above the ground.

To close the open upper end of the casing head 1 when the sprinkler is not in use, there is the closure disk 10 having the depending axial stem 11 passing through the 50 discharge orifice 7 of the nozzle head 3 and threadedly engaging the core 8. This closure disk is located a sufficient distance above the discharge orifice of the nozzle head that it will not interfere with the spray 55 discharged from the nozzle head. Also, the

stem 11 extends axially through the discharge orifice of the nozzle head and does not interfere with the passage of the water through this orifice.

The periphery at the upper end of the 60 casing head 1 is preferably bevelled as at 12 to be engaged by and to guide the depending annular peripheral flange 13 upon the closure disk 10 so that the latter will effectually close the casing head opening.

With the parts as shown in Figure 1, in which the sprinkler is not in use, the closure disk 10 is seated upon the upper end of the casing head 1 and closes its opening, and the nozzle head 3 is housed within the casing 70 head and suspended from the closure disk through its depending stem 11 and the core 8. Upon opening the valve controlling the supply of water to the stand pipe 2, this water upon rising into the casing head 1 75 raises the bell-shaped nozzle head 3 and with it the closure disk 10 until the annular flanges 5 and 6 upon the casing head and nozzle head respectively engage, after which the water passes through the nozzle head 80 only, the inclined grooves of the core producing a whirling action so that the water upon passing through the discharge orifice has the form of a conical spray. The closure disk is located sufficiently above the discharge orifice that it will not interfere with the spray, nor does its depending stem, due to its axial location in said orifice. Upon closing the valve controlling the supply of water to the stand pipe, the nozzle head 90 with the closure disk will lower owing to gravity until the closure disk is again seated upon the upper end of the casing head.

What I claim as my invention is:

1. The combination with a casing head 95 having an opening in its upper end, of a nozzle head movable vertically within said casing head and adapted to engage in said opening, a discharge orifice in the upper end of said nozzle head, a member within said nozzle head for effecting a whirling action of the liquid through said discharge orifice, and a closure for said opening in said casing head comprising a disk located sufficiently above said discharge orifice to be out of the 100 path of the liquid flowing therethrough, and a depending stem extending axially through said discharge orifice and carried upon said member.

2. The combination with a casing head 110

having an opening therein, of a nozzle head movable through said opening having a discharge orifice adapted to form a conical spray, a member extending axially through said discharge orifice and secured to said nozzle head, and a closure for said opening secured to the upper end of said member out of the path of the said conical spray.

3. The combination with a casing head having an opening in its upper end, of a nozzle head movable vertically within said casing head and adapted to engage in said opening, a discharge orifice in the upper end of said nozzle head, means within said nozzle head for effecting a whirling action of the liquid through said discharge orifice, and a closure for said opening in said casing head comprising a disk located sufficiently above said discharge orifice to be out of the path of the liquid flowing therethrough, and a depending stem extending axially through said discharge orifice and carried upon said nozzle head.

4. The combination with a casing head having an opening in its upper end, of a nozzle head telescopically engaging said casing

head and provided with a discharge orifice adapted to form a conical spray, means within said nozzle head for effecting a whirling motion of the liquid through said discharge orifice, a closure for the opening in said casing head arranged out of the path of said conical spray, said closure having a depending portion extending axially through said discharge orifice and secured to said nozzle head; and flanges on said casing head and nozzle head to limit the upward movement of said nozzle head and closure.

5. The combination with a casing head having an opening therein, of a nozzle head movable through said opening and provided with a discharge orifice, means within said nozzle head for effecting a whirling action of the liquid through said discharge orifice, and a closure for said opening in said casing head arranged out of the path of the liquid flow through said discharge orifice, said closure having a depending portion extending axially through said discharge orifice and secured to said nozzle head.

In testimony whereof I affix my signature.
EARL W. ROBERTS.
